SEDIMENT BULB FOR CARBURETORS

John E. Findley, Springfield, Colo.

Application November 10, 1948, Serial No. 59,206

4 Claims. (Cl. 210—57)

1

This invention relates to fuel cleaners and particularly sediment eliminators for fuel of internal combustion engines or engines of the diesel type, and in particular includes a comparatively small bulb, receptacle or vessel, positioned in the fuel supply line at a convenient point, preferably on the side of the engine and adjacent the carburator where it is readily accessible so that sediment may readily be removed from the bowl thereof, or wherein the bowl may readily be removed for cleaning and replaced by the average layman.

The purpose of this invention is to provide a device for removing sediment, dirt and the like from the fuel of internal combustion and other engines without removing the device from the fuel supply line in which it is installed.

Various types of filters, cleaners, and sediment eliminators have been used in the fuel supply lines of internal combustion and other engines and where the sediment collecting bowls are removed and replaced it is generally difficult to hold the sealing gasket in position and in some cases it is necessary to replace the gasket when the bowl is returned to the operative position. In devices where attempts have been made to clean the bowls without removing the bowls from the installation, it is necessary to use a wire or other cleaning implement or device to agitate the sediment so that it will run from the lower end of the bowl. With this thought in mind, this invention contemplates a sediment collector or eliminator having a removable bowl and also having a plug with an extended stem removably mounted in the lower end of the bowl wherein for ordinary cleaning, it is only necessary to remove the plug to drain the sediment from the bowl.

This invention also includes means for readily removing the bowl so that the entire device may be cleaned and the bowl supporting elements are so arranged that the bowl may also be readily replaced.

The object of this invention is, therefore, to provide means in a sediment eliminator for fuel supply lines of engines wherein the sediment may readily be removed.

Another object of the invention is to provide a removable plug in a sediment eliminator of engine fuel supply lines in which a projection of the plug extends upward into sediment that may be collected in the device wherein a drain hole provided in the lower end thereof is open as soon as the plug is removed.

Another object of the invention is to provide

2

a sediment eliminator bowl for collecting dirt and other foreign matter in fuel supply lines in which the inner surfaces of the walls slope outwardly toward the upper end to permit expansion of water that may have accumulated therein in extreme temperatures and particularly as the water freezes.

A further object of the invention is to provide a sediment eliminator for fuel lines of internal combustion and other engines which has a transparent bowl for collecting foreign matter in the fuel and in which the bowl may be cleaned without being removed from the supporting elements.

With these and other objects and advantages in view, the invention embodies a sediment eliminator having a head with fuel supply and outlet connections, a transparent bowl suspended from the underside of the head with a fine mesh screen and a gasket at the upper end of the bowl with means removably attaching the bowl to the head and with a cleaning plug removably mounted so that it extends into the lower end of the bowl to facilitate cleaning.

Other features and advantages of the invention will appear from the following description taken in conjunction with the drawings, wherein:

Figure 1 is a vertical cross-section through the sediment eliminator with parts shown in elevation;

Figure 2 is a view showing a side elevation of the device shown in Figure 1 with parts broken away and parts shown in section;

Figure 3 is a detail looking upward toward the lower end of the bowl of the eliminator and also with parts broken away;

Figure 4 is a detail showing a cross-section through the lower end of the bowl adapted to be used with the eliminator illustrating a modification wherein a circular groove is provided in the lower surface of the lower end of the bowl;

Figure 5 is a plan view of a gasket or packing disk adapted to be used with the bowl shown in Figure 4;

Figure 6 is a plan view of a support bar used for holding the bowl of the design illustrated in Figures 1 and 2;

Figure 7 is a view illustrating a further modification wherein a bayonet connection is provided at the upper end of the bowl and the cleaning plug is provided in a bushing in an opening in the lower end of the bowl;

Figure 8 is a plan view of the bowl shown in Figure 7;

Figure 9 is a cross-section through the head used with the bowl shown in Figures 7 and 8; and

Figure 10 is a detail showing an exploded view of the bushing and associated parts of the device shown in Figure 7.

Referring now to the drawings in detail, wherein like reference characters denote corresponding parts, the improved sediment eliminator of this invention includes a bowl 10 made of glass or other suitable transparent material, a head 11, a support bar 12 which is suspended from the head by bolts 13 and 14, and a cleaning plug 15.

The bowl 10 is described as being transparent, however it will be understood that a translucent material, metal, or any other suitable material may be used. As illustrated in Figure 1, the upper end of the bowl is provided with an annular recess 16 in which a relatively fine mesh wire screen 17 having a binding rim 18 thereon is positioned. The upper end of the bowl is formed with a rim 19 that is positioned in a recess 20 in the undersurface of the head 11 with a gasket 21 positioned in the recess and sealing the upper end of the bowl.

The bowl 10 is formed with sloping inner surfaces or walls 22 that slope outwardly and upwardly so that if water should accumulate in the bowl and freeze, it would bulge upwardly to prevent breaking of the bowl.

The lower end of the bowl 10 is provided with an opening 23 and a circular recess 24 is provided in the undersurface around the opening in which a gasket 25 is positioned which seals the opening around the stem 26 of the plug 15 and the gasket is clamped in place by the support bar 12 which is held by the thumb nuts 27 and 28 threaded on the lower ends of the bolts 13 and 14. The bolts 13 and 14 are freely held in bosses 29 and 30 on the sides of the head 11 with extending ends 31 and 32 on the upper ends of the bolts extending into openings in the bosses, as shown in Figure 2.

The plug 15 is formed with a threaded shank 33 on the end of which the stem 26 extends and the head of the plug is provided with wings 34 by which it may readily be gripped by hand. It will be understood that the head of the plug may be formed in any other manner wherein it may readily be gripped by hand or with a wrench or other tool. With the stem 26 extended upward into the interior of the bowl 10, the opening 23 will be open as soon as the plug is removed. This eliminates the necessity of sticking a wire or other device upward into the bowl to agitate sediment therein. The supporting bar 12 is provided with openings 35 and 36 through which the bolts 13 and 14 are extended, respectively, and with the lower ends of the bolts inclined inwardly, the upper ends will be securely held in the openings of the bosses 29 and 30 of the head.

The head 11 is provided with an inlet connection 37 having a threaded section 38 thereon, and an outlet connection 39 in which a bushing 40 may be threaded to hold the end of a fuel tube 41 in the connection of the head. The inlet connection 37 may be provided with a valve 42 having a packing gland 43.

With the parts arranged in this manner, the bowl 10 is clamped to the head 11 by the bolts 13 and 14 with the support bar 12 and the upper edge or rim of the bowl is positioned in the recess 20 in the undersurface of the head. Fuel passing through the device travels downwardly through the inlet connection as indicated by the arrows and then upwardly through the screen or filter 17, passing out through the connection 39. The device may remain in position while the sediment is removed by removing the plug 15 which is

threaded into the threaded opening 44 in the support bar 12. The plug is sealed in position by the gasket 25 and also by a gasket 45 under the head.

In the design shown in Figures 3 and 4, the lower end of a bowl 50, similar to the bowl 10, is provided with a centrally disposed opening 51 and an annular groove 52 is provided in the lower surface of the bowl and positioned concentric with the opening 51. With a bowl of this type, a packing washer 53 having an annular rib 54 positioned thereon to correspond with the groove 52 is clamped against the undersurface of the bowl by the bar 12, or any other suitable means. The gasket 53 is provided with a centrally disposed opening 55 that is positioned to register with the opening 51 in the bowl.

In the design illustrated in Figures 7, 8 and 9, a bowl 60 which is formed with a rim 61 around the upper end to correspond with the rim 19, is provided with sloping lugs 62 which are positioned to represent parts of screw-threads which coact with correspondingly shaped projections 63 in a recess 64 in the underside of a head 65 to secure the bowl in the recess of the head with a slight turning movement. The rim 61 of the bowl may be provided with a filter or screen similar to the device 17 and a gasket 66 is provided at the upper end to seal the bowl in the recess of the head.

In this design, the lower end of the bowl is provided with an opening 67 similar to the opening 23 and an internally threaded bushing 68 is positioned in the opening and held in place by a nut 69. Packing washers 70 and 71 are provided under the nut 69 and head 72 of the bushing, respectively. The sediment eliminator of this design is provided with a plug 73 having a threaded shank 74 and a stem 75 similar to corresponding parts of the plug 15. The head of this plug may also be provided with wings, as indicated by the numeral 76, to facilitate turning by hand or gripping elements of any type may be provided thereon.

With the parts arranged as illustrated in Figures 7 to 9, inclusive, it is only necessary to unscrew the plug 73 to remove sediment from the lower end of the bowl and when it is desired to remove the bowl for cleaning, the bowl is rotated until the lugs 62 are positioned between the projections 63, in which position the bowl may be dropped downwardly and separated from the head. The inner surface of this bowl and also of the bowl shown in Figure 4 converges toward the lower end similar to the inner surface 22 of the bowl 10 to prevent cracking of the bowl should water that may accumulate in the fuel therein, freeze.

It will be understood that other modifications may be made in the design and arrangement of the parts without departing from the spirit and scope of the invention.

What is claimed is:

1. A sediment eliminator comprising a head with inlet and outlet connections and having an annular recess in the lower surface, a transparent bowl having a centrally disposed opening in the lower end and with the inner surface of the wall thereof sloping outwardly toward the upper end, a support bar positioned against the lower end of the bowl, bolts clamping the support bar to the head, and a plug threaded in the support bar and having a stem extended upwardly through the opening in the lower end of the bowl and into the lower part of the bowl.

2. In a sediment eliminator for fuel supply

lines of internal combustion engines, the combination which comprises a cylindrical head having inlet and outlet connections therein and having an annular recess in the under surface, a support bar positioned below the head, bolts carried by opposite sides of the head extended through the ends of the said support bar and having nuts threaded on the lower ends for holding the said support bar, a collector bowl positioned below the head with the upper edge thereof in the said annular recess of the head and with the lower end spaced from the said support bar, said bowl having an opening extended through the lower end thereof, a sealing gasket positioned between the support bar and lower end of the bowl and a cleaning plug threaded in the said support bar and having a stem extended through the gasket and opening in the lower end of the said bowl.

3. In a sediment eliminator for fuel supply lines of internal combustion engines, the combination which comprises a cylindrical head having inlet and outlet connections therein and having an annular recess in the under surface, a support part positioned below the head, bolts carried by opposite sides of the head extended through the ends of the said support bar and having nuts threaded on the lower ends for holding the said support bar, a collector bowl positioned below the head with the upper edge thereof in the said annular recess of the head and with the lower end spaced from the said support bar, said bowl having an opening extended through the lower end thereof, a cleaning plug threaded in the said support bar and having a stem extended through the opening in the lower end of the said bowl, and a sealing gasket positioned between the said support bar and bowl and around the plug for sealing the opening in the lower end of the bowl.

4. In a sediment eliminator for fuel supply lines of internal combustion engines, the combination which comprises a cylindrical head having inlet and outlet connections therein and having an annular recess in the under surface, a support bar positioned below the head, bolts carried by opposite sides of the head extended through the ends of the said support bar and having nuts threaded on the lower ends for holding the said support bar, a collector bowl positioned below the head with the upper edge thereof in the said annular recess of the head and with the lower end spaced from the said support bar, said bowl having an opening extended through the lower end thereof, a cleaning plug threaded in the said support bar and having a stem extended through the opening in the lower end of the said bowl, and a sealing gasket positioned between the said support bar and bowl and around the plug for sealing the opening in the lower end of the bowl, said bowl having a cylindrical outer surface and a tapering inner surface with the internal diameter enlarging gradually toward the upper end.
